AIRPLANE

Melvin S. Emery, Oakland, Calif.

Application November 1, 1952, Serial No. 22,103

Term of patent 3½ years

(Cl. D71—1)

To all whom it may concern:

Be it known that I, Melvin S. Emery, a citizen of the United States and a resident of Oakland, Alameda County, California, have invented a new, original, and ornamental Design for an Airplane, of which the following is a specification, reference being had to the accompanying drawing forming a part thereof.

Figure 1 is a top perspective view of an airplane, showing my new design;

Figure 2 is a side elevational view thereof;

Figure 3 is a bottom plan view thereof; and

Figure 4 is a front elevational view of said airplane.

The dominant features of the design are indicated by the solid lines in the drawing.

I claim:

The ornamental design for an airplane, substantially as shown and described.

MELVIN S. EMERY.
